His Attorney.

UNITED STATES PATENT OFFICE.

ROBERT J. MULVEY, OF CHICAGO, ILLINOIS.

GARMENT FASTENER.

1,423,813.

Specification of Letters Patent. Patented July 25, 1922.

Application filed July 12, 1920. Serial No. 395,598.

To all whom it may concern:

Be it known that I, ROBERT J. MULVEY, a citizen of the United States, and a resident of the city of Chicago, county of Cook, and 5 State of Illinois, have invented certain new and useful Improvements in Garment Fasteners, of which the following is a specification.

My invention relates to improvements in 10 garment fasteners, and more particularly to the ordinary snap fasteners, the object of the invention being to provide improved means for securing the same in place.

Other objects will appear hereinafter. 15 The invention consists in the combinations and arrangements of parts hereinafter described and claimed.

The invention will be best understood by reference to the accompanying drawings 20 forming a part of this specification, and in which,

Fig. 1, is a top plan view of a fastener member embodying the invention,

Fig. 2, a bottom plan view of the same,

25 Fig. 3, a section of the same.

Fig. 4, a bottom plan view showing the fastener element secured to a piece of cloth, and

30 Figs. 5 and 6, views similar to Figs. 1 and 3 respectively, but illustrating a modified form of construction.

The form of construction illustrated in Figs. 1 to 4 inclusive comprises a disc 7 of sheet metal and having a central knob 8 35 adapted to constitute the male member of an ordinary snap fastener. The disc 7 is provided with a securing element adapted and arranged to secure the same to the cloth of a garment or the like. This securing element 40 is made of spring steel wire and has its end portions 9 secured in place on the under side of the disc 7 by means of a backturned securing flange or lip 10 as indicated, the end of said wire being circularly bent to fit under 45 said flange. A loop 11 is formed in said wire to project inwardly and laterally from under the flange 10 as shown. The body of the securing wire is tortuously bent into substantially S form 12 to fit within the flange 50 10 as shown, and the free end of the wire is provided with a hook 13 adapted to engage the loop 11.

In use, the body 7 is secured to the cloth 14 55 of a garment or the like by inserting the hook end 13 of the wire through an opening 15 in the cloth and then twisting the body 7

to force the body 12 of the wire through said opening as indicated in Fig. 4. Then the hook end 13 is passed through another opening 16 in the cloth and engaged with 60 the loop 11 thus firmly securing the body 7 in place on the cloth. By this arrangement, a simple and effective means for securing the body 7 to the cloth of a garment or the like is provided. By tortuously bending the 65 securing wire, the effect of a broad bearing or engagement with the cloth is produced, thus clamping, in effect, a considerable area of the cloth against the back of the body 7 and giving said body a wide and secure 70 bearing.

In the modified form of construction, illustrated in Figs. 5 and 6, the wire securing element is provided with a slightly different form of hook 13'. Otherwise, the construction 75 illustrated is identical with that already described.

While I have illustrated and described the preferred form of construction for carrying out my invention, this is capable of variation 80 and modification without departing from the spirit of the invention. I, therefore, do not wish to be limited to the precise details of construction set forth, but desire to avail myself of such variations and modifications 85 as come within the scope of the appended claims.

Having described my invention, what I 90 claim as new and desire to secure by Letters Patent is:—

1. A device of the class described comprising a body; a securing member therefor in the form of a wire having one end secured in operative relation to said body, the free portion of said wire being bent laterally into 95 tortuous form to provide a large engaging surface; and means at the free end of said wire for detachably securing the same to said body, substantially as described.

2. A device of the class described comprising a body; a securing member therefor in the form of a wire secured at one end to said body and bent into substantially S form surrounded by a circle of wire, and means at the free end of said wire for detachably 105 securing the same in operative relation to said body, substantially as described.

3. A device of the class described comprising a disc made of sheet metal and having a back turned securing flange at its edges; a 110 wire having one end substantially circular in form secured under said flange, the bight

- of said wire being tortuously bent; and
means at the free end of said wire for detachably securing the same in operative relation to said body, substantially as described.
5. A device of the class described comprising a disc made of sheet metal and having a back turned securing flange at its edges; a securing member therefor in the form of a wire having one end substantially circular
10 in form secured under said flange, the bight of said wire being bent into substantially S form; and means at the free end of said wire for detachably securing the same in operative relation to said body, substantially as described.
15. A device of the class described comprising a disc made of sheet metal and having

a back turned securing flange at its edges; a securing member therefor in the form of a wire having one end substantially circular 20 in form secured under said flange, the bight of said wire being bent into substantially S form; and a hook at the free end of said wire, there being a loop formed in the portion of said wire secured under said flange and 25 arranged and adapted to be engaged by said hook, substantially as described.

In testimony whereof I have signed my name to this specification in the presence of two subscribing witnesses.

ROBERT J. MULVEY.
